Primary Examiner—Cathron C Brooks*Assistant Examiner*—Austin Murphy(74) *Attorney, Agent, or Firm*—Rhonda L. Barton; Scott B. Markow; Adan Ayala(57) **CLAIM**

The ornamental design for a planer, as shown and described.

DESCRIPTION

FIG. 1 is a perspective view of a planer showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines shown in the drawings represent unclaimed portions of the planer and form no part of the claimed design.
